ASSIGNORS TO PACKAGE MACHINERY COMPANY, OF SPRINGFIELD, MASSACHU-
SETTS, A CORPORATION OF MASSACHUSETTS.

SLAB CUTTING AND SEPARATING MACHINE.

1,108,204.

Specification of Letters Patent. Patented Aug. 25, 1914.

Application filed April 29, 1913. Serial No. 764,412.

To all whom it may concern:

Be it known that we, FREDERICK H. MERRELL and WILLIAM K. BLACKBURN, both citizens of the United States, and residents of 5 Milwaukee, in the county of Milwaukee and State of Wisconsin, have invented certain new and useful Improvements in Slab Cutting and Separating Machines; and we do hereby declare that the following is a full, 10 clear, and exact description thereof.

The primary object of our invention is to provide an accurate, economical, speedy automatic machine for cutting slabs of predetermined dimensions into rows of bricks or 15 cubes of equal dimensions or weights and for individually separating such cubes and delivering the same one by one to a receiver, which receiver, as expressed diagrammatically in the drawings, may constitute 20 part of a wrapping machine of that general type such, for example, as disclosed in patents issued to J. M. Patterson for improvements in wrapping machines, No. 869388, Oct. 29, 1907, and 874620, Dec. 24, 25 1907, it being understood that the slabs of material to be worked upon may be any soft pliable material such as butter, soap, frozen dainties, or the like.

Specific objects of our invention are to 30 provide an alined series of fixed cutting members for separating the slab into a row of cubes; to provide a positively movable follower strip for feeding the slabs to a line of cutters; to provide a positively movable 35 spotter-foot arranged at a right angle to the follower strip that co-acts with a fixed gage-strip at the opposite end of said follower-strip, whereby a slab is alined with the cutters and fed thereto for separation into a 40 row of cubes; to provide a longitudinally arranged cube-receiving tray section for the row of cubes beyond the line of the cutters; to provide a pair of longitudinally disposed 45 intermittently movable feeder-hands for delivering the row of cubes to a separator; to provide a reciprocative receiver into which the separator delivers the cubes; to provide an endless carrier connection between the feeder-hands; to provide a cam-controlled 50 means for shifting the feeder-hands from a working to an idle position after a complete feed movement, whereby the previous idle hand is brought into working position in alinement with the first cutting member

of the series co-incident to the delivery of a 55 row of cubes in its path of travel; to provide a cam-controlled rack-bar for moving the feeder-hands intermittently or step by step in alinement with each cutting member; to provide means for adjusting the feeder-hands, whereby the capacity of the machine 60 may be varied, together with means for varying the ratio of the gearing in proportion to said capacity; to provide a cam-controlled separator together with a presser- 65 foot, whereby the forward brick or cube is broken away from the held succeeding brick, the separated brick being delivered to the receiver; to provide a gear connection between the receiver and driving gear of the 70 cutting and separating machine whereby the cubes are cut, separated and delivered one by one to a wrapping machine in timed relation to its operation, and to provide means for locking and releasing the feeder- 75 hand shift mechanism.

With the above and other minor objects in view the invention consists in certain peculiarities of construction and combination of parts as hereinafter set forth with reference to the accompanying illustrations and subsequently claimed.

In the drawings Figure 1 represents a side elevation of a cutting and separating machine embodying the features of our invention with parts broken away and parts in section to more clearly illustrate certain structural features, the reciprocative receiver arm of a wrapping machine being shown in connection with the cutting machine in its position of delivery to said wrapping machine; Fig. 2, an end elevation of the machine; Fig. 3, a plan view of the same partly in section as indicated by line 3-3 of Fig. 1; Fig. 4, a sectional plan view illustrating particularly the gear mechanism, the section being indicated by line 4-4 of Fig. 1; Fig. 5, a detailed fragmentary elevation of the feeder-hand trip mechanism upon an enlarged scale; Fig. 6, a similar view of said mechanism showing the parts in their shifted position; Fig. 7, a detailed sectional plan view of said feeder-hand shift mechanism, the section being indicated by lines 7-7 of Figs. 2 and 5; Fig. 8, a longitudinal sectional view of the same, the section being indicated by lines 8-8 of Figs. 3 and 5; Fig. 9, a detailed transverse sectional view

through a portion of the table and its receiving tray section at the discharge end thereof, said view also illustrating the feeder-hand runway mechanism, the section 5 being indicated by line 9—9 of Fig. 3; Fig. 10, an enlarged detailed longitudinal section view through the receiving tray at its discharge end and separator, the section being indicated by line 10—10 of Fig. 3; Fig. 10^a, a detail plan section view of the separator; Fig. 11, a detailed sectional view through the separator and receiving tray showing the same in a cube-breaking position; Fig. 12, a diagrammatic view of the 15 separator and cube receiver, which receiver constitutes part of a wrapping machine mechanism as shown, the said wrapping machine mechanism being in gear connection with the cutting and separating machine; Fig. 12^a, a detailed cross-section of the wrapping machine plunger taken on line 12^a—12^a of Fig. 12; Fig. 13 represents an enlarged detailed sectional view of one of the 20 feeder-hands and its carrying mechanism, together with a portion of the receiving tray, the section being indicated by line 13—13 of Fig. 15; Fig. 14, a detailed side elevation of the same with portions broken away showing the rack-bar and pawl engaging means with the shoe; Fig. 15, an inverted sectional plan view of the feeder-hand mechanism, the section being indicated by line 15—15 of Fig. 13; Fig. 16, a detailed sectional view through the ears of the shoe 30 14' showing the means for adjustably connecting the shoe to the belt, the section being indicated by line 16—16 of Fig. 13; Fig. 17, a sectional view through the ears of the shoe 14" illustrating the means for 35 connecting one of the belt ends thereto; Fig. 18, a detailed sectional view of a spotter-foot mechanism, and Fig. 19, a sectional elevation upon an enlarged scale of a transmission gear mechanism employed for varying the speed of the machine.

Referring by characters to the drawings 1 represents the corner legs and 2, 3, upper and lower integral connecting bars respectively, of a supporting frame, which frame 50 is also provided with lower transverse struts 4 and an upper bed-plate 5 that is suitably secured to the legs. The bed-plate 5 carries a table 6 having a slightly depressed longitudinally disposed receiving tray section 7 at its discharge edge. Standards 8 project upwardly from the bed-plate 5 for the support of an overhead bridge-bar 9, to which bar and the bed are secured an alined series of wire strand cutting members 10 55 that are longitudinally arranged parallel to the discharge edge of the table at its junction with the tray section thereof, the said cutting members being set at equal distances apart, the first of which series 10' constitutes a trimmer.

As best shown in Figs. 2 and 3, the table carries a longitudinally disposed slidable follower strip 11 that is provided with a series of kerfs in its working face for the admission of the cutting members whereby 70 said follower strip, when moved forward to its limit, will effect a complete cutting operation through a slab of material carried thereby. One edge of the follower strip is arranged in slidable engagement with a 75 gage-strip 12 that is transversely secured to an edge of the table, there being a reciprocative spotter-foot 13 mounted adjacent to the opposite edge of the table clear of the path of travel of the follower strip which is automatically moved forward slightly in advance of the follower strip movement whereby a rectangular slab of material of predetermined area is adjusted in position 80 against the gage strip 12 to thus align the slab in its proper cutting position relative to the line of cutting members. Forward movement of the follower strip will thus sever the entire slab into separate cubes as it is forced between and through the cutting 85 members. After the slab is so divided into cubes of predetermined area or weight they are deposited upon the receiving tray section 7 and the entire row of cubes are thereafter fed transversely toward the discharge 90 end of the receiving tray intermittently or step by step a distance equal to the width of a cube unit at each feed movement. This feed of the line of cubes is accomplished by one of a pair of feeder-hands 14, which 95 feeder-hands engage the outer face of the rear cube and push the entire series or row forwardly upon the tray, the feeder-hand being initially positioned in alinement with the first cutting member 10' of the series, the 100 said cutting members, as previously stated, constituting a trimmer, whereby the spotter foot engaged end of the slab is trued. The feeder-hands 14 extend from individual shoes 14', 14", that are slidably mounted 105 upon a longitudinally disposed double runway, the same being composed of parallel rails 15, which rails are connected at their ends and carried by furcated heads 16, 16'. The heads have projecting spindles 17, 17' 110 respectively, which spindles are journaled in boxes that are carried by brackets 18, the same extending upwardly from the opposite ends of the machine frame. Journaled between the furcated members of each head is 115 a flanged wheel 19 for the reception and support of an endless belt carrier 20 that is preferably in the form of a metallic tape. The feeder hand shoe 14" forms a connecting link between the tape ends of one stretch 120 of the belt, the said connection being effected by blocks 21, which blocks are permanently secured to the tape ends and are fitted between ears 22 of the shoe. The blocks are 125 provided with tie-bolt end shanks which are 130

secured to the ears 22 by suitable washers and bolts 23, the same being in spanner engagement with the ear edges whereby the belt may be drawn taut. The opposite 5 feeder-hand shoe 14' is similar in construction to the first mentioned shoe but is adjustably secured to the opposite stretch of the belt 20 by means of a permanently attached apertured block 24, which block is secured 10 between one or the other set of ears 22' of the shoe 14' by means of a cotter-pin 25 that is fitted through the block aperture and corresponding apertures with which each set 15 of ears is provided, the said cotter-pin being held in position by a snap-spring 26, one of which is carried by each set of ears as best shown in Fig. 13. It should be understood that the feeder-hands 14 are extended in opposite directions from the belt stretches 20 and when forward movement is imparted to the working feeder-hand its idle companion upon the opposite belt stretch is caused to travel through its connection with the belt to a point in alignment with the first cutting 25 member 10', at which point it is rotated coincident to a corresponding reverse rotation of the opposite feeder-hand, the same being at this time at the end of its working stroke and adjacent to the discharge end of the receiving tray.

Intermittent feeding movement is imparted to each feeder-hand by a vibratory rack bar 27 that is arranged parallel to the feeder-hand runway, teeth of the rack being 30 adapted to engage spring-controlled pawls 28, one of which is pivoted to a web 29 of each feeder-hand shoe and so positioned that when said feeder-hand has swung into action the nose of the pawl will align with 35 the rack-bar, whereby movement thereof will positively cause forward travel of the feeder-hand a distance equal to the width of a cube unit, the rack-bar being then returned so that in its next forward movement 40 the preceding tooth thereof will act upon the pawl resulting in a succession of step by step forward impulses of the working feeder-hand, which impulses correspond in 45 number to the number of cubes of material 50 that are to be fed.

Motion is imparted to the vibratory rack-bar 27 by a feeder-hand cam-wheel 30 as best shown in Fig. 1, which cam wheel is secured to a driven shaft 31 that is journaled in suitable 55 bearings with which the frame bars 3 are provided. With each revolution of the shaft the cam-wheel 30 imparts oscillatory movement to a bell-crank lever 30', having one arm that engages a cam-wheel, while its 60 opposite arm is connected by a link 32 to the rack-bar 27, it being understood that said rack-bar is suitably mounted in boxes 33 that project upwardly from the adjacent upper bars 2 of the frame.

65 The means for simultaneously shifting the

opposite feeder-hands in and out of working position at the end of their longitudinal travel, as best shown in Figs. 5 to 9 inclusive, comprise a mutilated pinion 34, the same being loosely mounted upon the spindle 70 17 of the head which forms one member of the double runway that serve as guides for the feeder-hands. An arm of the mutilated pinion 34 carries a spring-controlled clutch-pawl 35, the nose of which is positioned to engage one of a pair of oppositely disposed notches 36, 36', that are formed in the face of a hub 37, the hub being rigidly secured to the head spindle 17 adjacent to the mutilated pinion. A bracket 38 is secured 75 to the frame adjacent to the head spindle box-carrying bracket 18 and upon a stud 39 of the bracket 38 is loosely mounted a locking dog 40, the nose of which locking dog is normally seated in one of the hub 80 notches 36, 36'. The locking dog is also provided with a spanner arm having an end cam 41, which cam normally overlaps the disengaged notch of the hub. Presuming 85 that the locking dog 40 is in engagement 90 with the notch 36 of the hub as shown in Fig. 5, and is thereafter released, it is apparent that a half revolution of the hub 37 can be effected by oscillating the mutilated pinion 34 in a direction indicated by the 95 arrow in Fig. 5. This movement of the mutilated pinion will cause its clutch pawl 35 which is now seated in the notch 36 to carry the hub in its travel to the position shown in Fig. 6 of the drawings. Co-incident 100 to this movement a spring-controlled trip mechanism, to be hereinafter described, will cause the locking dog nose to drop into the now registered hub notch 36'. The spanner arm cam 41 will then assume its normal 105 position bridging the open end of the notch 36 and in this aligned position of the cam a spur 42 of the spring-controlled clutch pawl will engage the face of the cam and thus lift the nose of the clutch pawl from 110 engagement with the hub notch 36 and hence the entire runway together with the feeder-hands will describe a semi-revolution about the spindle axis, in which shifted position said mechanism is again held by the locking 115 dog due to the fact that the same has now entered the opposite notch 36 of the hub. Positive rotation of the mutilated pinion 34 is effected through its engagement with a toothed sector 34' that is also journaled 120 upon the bracket-stud 39 and is provided with a roller-carrying arm 42, which arm engages the slotted end 43 of a floating link 44, the same being provided with adjustable tappet bolts to limit the movement of said 125 sector arm.

The spring-controlled trip mechanism for releasing the locking dog 40 from the runway hub 37 comprises a wrist-plate 45, which wrist-plate is pivotally secured to the 130

4
 bracket 38 by means of a stud 46 that extends from the wrist-plate. The wrist-plate 45 is connected by a tie-rod 47 to the locking dog, there being a coiled spring 48 that forms a tie connection between an arm of the wrist-plate and a crank-arm 40' of said locking dog. The wrist-pin stud 46 also carries a tappet finger 49, which finger is in the path of travel of a tappet lug 50 that projects from the slotted end 43 of the floating link.

From the foregoing description it is apparent that the locking dog and wrist-plate are mounted upon spaced fixed points as shown and connected by a positive tie-rod together with a spring and hence the spring will exert force to draw the locking-dog crank-arm 40' and wrist-plate together, whereby the tie-rod connection between the wrist-plate and said locking-dog will exert constant spring force to hold the nose of this dog against the face of the hub. It follows that downward force applied to the floating link 44 will first impart motion to the wrist-plate through the tappet members 49 and 50, whereby the locking mechanism of the feeder-hand runway will be released and a further downward movement of said floating link will, through its engagement with arm 42 of the sector, cause rotation of the feeder-hand runway about its axis, it being understood that the tappet mechanism is so timed that release of the locking-dog from its position clear of the hub is not effected until said hub has been initially rotated, whereby its notch is moved out of alignment with the nose of the locking-dog. After the spring-controlled runway lock and release mechanism has been actuated and the parts assume the position as shown in Fig. 6 of the drawings, with the clutch pawl 35 held free of the notched hub. It is obvious that an upward movement of the floating link 44 will simply cause the same to engage the sector arm 42 and reverse direction of rotation of the clutch pawl and its pinion 34, the nose of which pawl will now initially ride over the cam-face 41, whereby the head notch 36' is bridged and the pawl is returned to its seat in the notch 36', there being no movement of the locking-dog in the recovery stroke of the mechanism, due to the fact that the tappet members carried by the wrist-plate and floating lever will yield co-incident to upward engagement thereof. The floating link and shift movement of the feeder-hand runway is brought into operation once only in a cycle of the other operations of the machine or after each slab has been completely disposed of, the time of operation being determined by the number of cube units into which the slab is divided.

The shift movement of the feeder-hands 65 is controlled by a combined feeder-hand

trip and follower strip actuating cam-wheel 51, which cam-wheel for simplicity in construction is formed integral with a spotter-foot cam-wheel 52 that actuates a bell-crank lever 53, the same being linked to a cross-head 54, which cross-head is slidably mounted upon a guide-rod 55 that extends outwardly from one end of the bed-plate 5. The cross-head 54 extends upwardly through an end-slot in the table 6 and carries the shank-pin 56 of a backing bracket 57, which bracket is secured to the slideable spotter-foot 13. It is apparent that by timing of the cam-wheels 51 and 52, preceding each forward movement of the follower strip, the spotter-foot moves transversely and forces the slab of material to be cut against the gage-strip 12', whereby said slab is alined to receive divisional cuts as it is forced through the line of cutting strands 10.

The forward and return movement of the follower strip is effected by arms 58 that are carried by a longitudinally arranged rocker shaft 59 which is journaled in suitable bearings extending from the frame, the upper ends of the arms being connected to the follower strip 11 by links 58'. The rocker-shaft 59 also carries a crank-arm 60 as best shown in Figs. 1, 2 and 4, which crank-arm 95 is linked to a lever 61 that carries a roller for engagement with the feeder-hand and follower strip actuating cam-wheel 51. The end of the crank-arm 60 is also connected to the lower end of the floating link 44 which 100 actuates the feeder-hand shift mechanism, the upper slotted end of the floating lever being guided through its roller connection with the segment arm 42. Hence it follows that when the cam-wheel 51 is positioned 105 relative to the lever 61 as shown in Figs. 1 and 2 of the drawings, that the follower strip is in its extreme forward position. In this position the shift mechanism assumes the position shown in Fig. 2, having previously released the locking dog 40 through the trip mechanism and reversed the position of the feeder-hands, whereby feeder-hand α , as indicated in Fig. 2, has swung from an idle to its working position, feeder-hand marked γ being at the end of its feed stroke and is shifted to an idle position. The feeder-hand α is thus alined with the first or trimmer cutter 10' and in abutting engagement with the now cut slab of material which 110 is resting upon the receiving tray 7 of the table, it being understood, by reference to Fig. 3, that shift of an idle feeder-hand to working position takes place beyond the end of said receiving tray. Each cube of the severed slab of material is successively pushed over the discharge end of the receiving tray 7 into a separator A, the same comprising a rectangular metallic skeleton 115 frame having a solid bottom 62 and rear- 120

wardly disposed rest bars 63, against which a cube of material abuts when the same is forced into the open throat of said receiver, the separator being in its normal position of 5 rest as shown in Fig. 10 of the drawings. When the separator is in the above referred to position its bottom 62 registers with and forms a continuation of the receiving tray and is supported in this position by forwardly extended toggle links 64 that have 10 fixed pivoted pins 64' which are carried by ears of brackets 65 that are extended from the bed-plate 5. The free ends of the toggle links are pivotally connected with the lower 15 front corner of the skeleton frame adjacent to its floor line and the upper corner of the separator frame is hinged to and between a pair of elbow levers 66, which elbow levers in turn are secured to a cross-rod 67 that is 20 journaled in the bed-plate brackets 65. One of the elbow levers 66 carries a pitman-rod 68 that is also hinged to one arm of a bell-crank lever 69, the opposite arm of said bell-crank lever being provided with a roller that 25 engages a separator actuating cam-wheel 70. This cam-wheel 70 is, for convenience in construction, shown integral with the rack-bar actuating cam-wheel 30 as clearly shown in Figs. 1 and 2 of the drawings.

30 From the foregoing description it is apparent that owing to the timed relation between the rack-bar actuating cam-wheel 30 and separator actuating cam-wheel 70 that with each discharge of a cube of material 35 into the separator, the rear end of said separator is initially depressed by action of the elbow lever 66, the same moving in an arc of a circle in the direction as indicated by the arrow Fig. 11. This initial depression 40 of the rear end of the separator is caused through a rocking movement upon its fulcrum points with reference to the toggle links 64, there being no appreciable movement of said links, due to the fact that the load of the separator is sustained by its suspension from the elbow levers. Thus the 45 cube of material is separated from the succeeding cube by swing of the separated cube upon an imaginary point at the base of the cut, the separation taking place from top to bottom in an operation similar to an opening jaw movement, whereby a clean break is effected, it being understood that in practice even though the cubes have been severed, more or less adhesion therebetween 50 takes place due to the forward impact of the row of cubes in a feed movement. Continued movement of the forward actuating separator levers 66 in the same direction causes the toggle links to describe a semi-circular lifting movement about their fixed axis and the separator carried thereby will 55 make a half turn about its toggle link axis, coming to rest in an inverted position after such planetary movement, whereby the cube

contained therein is deposited bottom side up into an L-shaped receiver 71 that is now positioned between the rest-bars 63 of the separator frame. Thereafter forward movement is imparted to the receiver, whereby 70 its back member will strip the cube from the separator through which it passes and deliver said cube to a wrapping machine as shown in the diagram view Fig. 12, for further operation, it being apparent that 75 the planetary movement imparted to the separator will serve also to permit the same to ride over and clear the receiver, which would otherwise be at rest in its path of travel should said separator be moved outwardly upon an even plane. Prior to a separating operation of the cubes from the tray-carried group and just after a cube has been seated within the separator box a presser-foot 73 is, with delicate nicety, 80 caused to engage the succeeding cube, whereby the latter is held firmly during said separating operation. The presser-foot 73 is carried by a vibratory lever 74, which lever is pivoted to the adjacent bridge 85 standard 8 and is connected by a pitman rod 75 to a spring pressed lever 76, the latter having one end in engagement with a presser-foot cam-wheel 77 that is rigidly secured to the drive-shaft 31, whereby said 90 presser-foot is actuated in timed relation following each forward movement of the feeder-hands. As shown in the diagram view Fig. 12 the receiver 71 delivers the print or cube of material over a well *a* of a 100 wrapping machine such, for example, as disclosed in the patents hereinbefore mentioned. This wrapping mechanism is provided with a crank-driven walking-beam whereby motion is transmitted to the oscillatory receiver 71, the crank-shaft *b* of which machine is in gear connection with the cutting and separating machine. The receiver 71 deposits the cube between a yielding gripping wall *c* and the side-wall of a 105 plunger-head *d*, whereby the cube is held in suspension in alignment with the well and a wrapping blank *e* thereunder, which blank is fed over the mouth of the well by a suitable feed mechanism. Thereafter the plunger head 110 is forced downwardly through the well together with the cube of material and wrapper blank, whereby the latter is suitably folded about said cube. The means for folding such wrappers forms no part of our invention and is fully disclosed in the above 115 referred to patents.

The ten and twelve ratio of rotation of the cams relative to the driven shaft 31 and various cams is obtained through a gear-train comprising a pinion 78 that is fast upon the driven shaft and adapted to intermesh with a second interchangeable pinion 79, which pinion is loosely mounted upon a 120 stud carried by a manually shiftable arm 130

6

80 as best shown in Figs. 4 and 19 of the drawings. The shiftable arm 80 is fulcrumed upon an arbor 81, which arbor is journaled in a suitable bearing-hub extending from one of the frame bars 3. Meshing with the idle pinion 79 is a gear-wheel 82, the same being secured to one end of the arbor 81, and the opposite end of said arbor carries a pinion 83, which, in turn, is meshed 10 with a gear-wheel 84 that is secured to one end of a sleeve 85, the latter being loosely mounted upon the driven shaft 31 and is secured to the cam-wheels 51 and 52. These cam-wheels thus rotate at a reduced speed 15 relative to the driven shaft but in the same direction as the latter. Hence it is apparent that the speed of the cam-wheels 51 and 52 can be increased with relation to the speed of the driven shaft by substituting a slightly 20 larger pinion for the pinion 78, whereby a reduction in the number of cubes of material to be cut is provided for in the timing of the cutting mechanism relative to the cube feeding mechanism. It follows that the shiftable arm 80 must be slightly raised and 25 locked in such raised position when a larger pinion is required. This is effected by a locking bolt 86, which locking bolt is shifted to the registered apertures 87, 87', that are 30 formed in a web of the frame bar member 3, the said apertures corresponding to a similar set in which the locking bolt is shown in Fig. 19 of the drawings for holding 35 the arm and its idle pinion in mesh with the driven pinion. The driven shaft, as best shown in Figs. 4 and 19, receives its motion in this instance from an endless chain belt 88, which belt engages a sprocket-wheel 89 on the shaft and a corresponding 40 sprocket-wheel 90 that is mounted upon the wrapping machine crank-shaft *b*, it being understood that said crank-shaft is driven by a motor or other suitable means.

As shown in Fig. 3, the follower strip is 45 provided with a detachable end section 11' which is removed when the capacity of the machine is restricted to a ten cube cutter, it being apparent that the scope of the adjustment of all of the parts may be varied 50 as conditions may require.

We claim:

1. A slab-cutting and separating machine comprising a series of alined fixed cutters, a slab-engaging follower arranged to one side 55 of the cutters, actuating means for the follower whereby a slab of material is fed through the series of cutters to divide the same into cubes, a separator disposed adjacent to one end of the line of cutters and upon that side opposite the follower, and an intermittently movable cube feeder arranged 60 transversely of the cutters in alinement with the separator.

2. A slab-cutting and separating machine 65 comprising a series of equally spaced alined

fixed cutters, a slab-engaging follower strip arranged to one side of the cutters, actuating means for the follower strip whereby a slab of material is fed through the series of cutters to divide the same into cubes, a separator disposed adjacent to one end of the line of cutters and upon that side opposite the follower strip, a cube feeder arranged transversely of the cutter in alinement with the separator, an intermittent feed mechanism for the cube feeder.

3. A slab-cutting and separating machine comprising a series of alined fixed cutters, a slab-engaging follower arranged to one side of the cutters, actuating means for the follower whereby a slab of material is fed through the series of cutters to divide the same into cubes, a rocking separator disposed adjacent to one end of the line of cutters and upon that side opposite the follower, and an intermittently movable cube feeder arranged transversely of the cutters in alinement with the separator.

4. A slab-cutting and separating machine comprising a table adapted to receive a slab of material to be cut, a series of alined fixed cutters extending above the table, means for feeding the slab of material through the cutters whereby it is divided into sections, means for feeding the group of separated slab sections longitudinally of the line of cutters intermittently at distances equal to the width of the separated slab sections, a separator arranged to receive the forward slab section of the series, and actuating means for the separator whereby the slab contained therein is broken from the succeeding slab.

5. A slab-cutting and separating machine comprising a series of alined fixed cutters, a slab-engaging follower strip arranged to one side of the cutters, actuating means for the follower strip, a separator disposed adjacent to one end of the line of cutters and upon that side opposite the follower strip, actuating means for the separator, a feeder arranged transversely of the cutters in alinement with the separator, intermittent actuating means for the feeder, and a correlated gear connection between the follower actuating means, separator actuating means and feeder actuating means.

6. A slab-cutting and separating machine comprising a series of alined fixed cutters, a slab-engaging follower arranged to one side of the cutters, actuating means for the follower whereby a slab of material is fed through the series of cutters to divide the same into cubes, a separator disposed adjacent to one end of the line of cutters and upon that side opposite the follower, an intermittently movable cube-feeder arranged transversely of the cutters in alinement with the separator, and a movable receiver arranged to receive the separated cubes.

7. A slab-cutting and separating machine comprising a series of alined fixed cutters, a slab-engaging follower arranged to one side of the cutters, actuating means for the follower whereby a slab of material is fed through the series of cutters to divide the same into cubes, a gage-strip arranged in juxtaposition to one end of the follower, a cam-controlled spotter arranged at the opposite end of the follower, a separator disposed adjacent to one end of the line of cutters and upon that side opposite the follower, and an intermittently movable cube feeder arranged transversely of the cutters in alinement with the separator. 70
8. A slab-cutting and separating machine comprising a table, a series of alined cutters extending above the table, a slab engaging follower strip slidably mounted upon said table to one side of the cutters whereby a slab of material is fed through the series of cutters and divided into cubes, a separator disposed adjacent to one end of the table upon that side of the cutters opposite the follower strip, and a feeder-hand arranged to travel parallel with the cutters and in alinement with the separator. 80
9. A slab-cutting and separating machine comprising a table, a series of alined cutters extending above the table, a slab engaging follower strip slidably mounted upon said table to one side of the cutters whereby a slab of material is fed through the series of cutters and divided into cubes, a separator disposed adjacent to one end of the table upon that side of the cutters opposite the follower strip, an intermittently movable feeder-hand arranged to travel parallel with the cutters in alinement with the separator, an actuating cam in link connection with the separator, an actuating cam in link connection with the intermittent feeder-hand mechanism, means for driving said cams at a uniform speed in the same direction, a cam in link connection with the follower strip, and means for driving the cam in the same direction and at a lower speed than the first mentioned cams. 90
10. A slab-cutting and separating machine comprising a table, a series of equally spaced alined fixed cutters extending above the table, a slab-engaging follower strip arranged to one side of the cutters, cam-controlled actuating means for the follower strip whereby a slab of material is continuously fed through the series of cutters and divided into cubes, a cam actuated separator disposed adjacent to one end of the line of cutters and upon that side opposite the follower strip, a rotatory runway arranged parallel with said line of cutters, feeder-hands slidably mounted thereon, and a cam-controlled intermittent feed mechanism for the feeder-hands. 100
11. A slab-cutting and separating machine comprising a series of alined fixed cutters, a receiving tray disposed upon one side of the line of cutters and parallel thereto, a follower disposed upon the opposite side of the line of cutters arranged to feed a slab of material through said cutters whereby it is divided into cubes that are deposited upon the receiving tray, a rotatory runway arranged parallel with the receiving tray, an endless belt carried thereby, feeder-hands carried by the belt, means for imparting intermittent movement to one of the feeder-hands whereby the latter is moved step by step longitudinally of the receiving tray, and means for rotating the runway incidental to a complete step by step movement of the feeder-hands. 110
12. A slab-cutting and separating machine comprising a series of equally spaced alined fixed cutters, a slab-engaging follower strip arranged to one side of the cutters, actuating means for the follower strip whereby a slab of material is fed through the series of cutters and divided into cubes, a receiver disposed adjacent to one end of the line of cutters and upon that side opposite the follower strip, and an intermittently movable cube-feeder in alinement with the receiver. 120
13. A slab-cutting and separating machine comprising a table having a receiving extension, a series of alined fixed cutters extending above the table, a slab-engaging follower mounted upon the table, actuating means for the follower strip whereby a slab of material is fed through the series of cutters and divided into cubes, a rocking separator disposed adjacent to one end of the receiving tray, a cam-controlled actuating mechanism therefor, a rotatory runway disposed parallel with said receiving tray, an endless belt carried thereby, a series of feeder-hands mounted upon the runway adapted to travel upon the receiving tray, means connecting the feeder-hands and belt, means for releasing and locking the runway against rotation, cam-controlled actuating means for the runway lock and release mechanism, and a vibratory feed-bar for the feeder-hands. 130
14. A slab-cutting and separating machine comprising a series of fixed cutters, a slab-engaging follower, actuating means therefor whereby a slab of material is fed through the series of cutters and divided into cubes, a receiving tray arranged parallel with the line of cutters upon that side opposite the follower, a rotatory runway arranged parallel with the receiving tray, means for rotating the runway, cam-controlled lock and release means in connection with the runway rotating means, feeder-hands mounted upon the runway extending in opposite directions, a belt carried by said runway, means for adjustably locking the 140

feeder-hands to the belt, and intermittent feed mechanism for the belt-carried feeder-hands.

15. A slab-cutting and separating machine comprising a series of alined fixed cutters, a slab-engaging follower strip arranged to one side of the cutters, actuating means for the follower strip whereby a slab of material is fed through the series of cutters and divided into cubes, cam-actuated levers disposed adjacent to one end of the line of cutters and upon that side opposite the follower strip, a rectangular separator having its upper end pivoted to the levers, fulcrumed links having their free ends secured to the lower portion of the rectangular separator, means for feeding the divided cubes into the separator, and a reciprocative receiver arranged to receive individual cubes from the separator.
16. A slab-cutting and separating machine comprising a line of cutters, means for feeding rectangular slabs through the cutters whereby they are divided into cubes, a receiving tray for the severed cubes, means engaging the last cube of the severed series, whereby said series is fed forward, intermittent actuating means for the cube-engaging means, an open mouthed separator arranged to normally rest against one end of the tray whereby cubes are fed therein, a receiver in alinement with the separator, and means for effecting a planetary movement of the separator whereby the same is inverted and its contents discharged into the receiver.
17. A slab-cutting and separating machine comprising a frame, a table mounted thereon having a tray extension, a series of equally spaced alined cutters extending upwardly through the table, a follower strip, a rock-shaft in link connection with the follower strip, cam-controlled actuating means for the rock-shaft, a gage-strip arranged in juxtaposition to one end of the follower strip, a cam-controlled spotter-foot in juxtaposition to the opposite end of the follower strip, a double track runway arranged parallel with the receiving tray table section, spindles extending from the runway, journals for the spindles carried by the frame, feeder wings mounted upon the runway tracks and extending in opposite directions adapted to engage the receiving tray, means for imparting reciprocative motion to one of the feeder-hands, an endless belt carried by the runway connecting said feeder-hands, a notched hub secured to one of the runway spindles, a pinion loosely mounted upon the said spindle, a pawl carried by the pinion engageable with the hub notches, a cam actuated toothed sector engageable with the pinion, a spring-controlled lock and release dog engageable with the hub notches, and a tappet mechanism for controlling said lock and release dog.

18. In a slab-cutting and separating machine having a series of alined fixed cutters, means for feeding slabs to the fixed cutters, and means for separating the cut slabs; the combination of a slab feed mechanism for the separator comprising a rotatory runway having a spindle extension, feeder-hands mounted upon the runway extending in opposite directions, means for imparting intermittent movement to one of the feeder-hands, an endless belt carried by the runway connecting the feeder-hands, clutch members carried by the runway spindle, means for effecting clutching engagement between the clutch members whereby the runway is given a partial rotation, and means for locking the runway after each partial rotation.

19. In a slab-cutting and separating machine having a series of cutters, means for feeding slabs through the cutters whereby they are divided into cubes, a receiving tray for the cubes, and a separator arranged to receive the cubes at one end of the tray; the combination of a double track rotatory runway mounted parallel with the tray, a shoe in slidable union with each runway, feeder-hands extending from the shoes in opposite directions adapted to engage the receiving tray, whereby the slabs are fed to the separator, an endless belt carried by the runway, means connecting the respective feeder-hand shoes with opposite stretches of the belt, pawls carried by the shoes, a rack-bar disposed in the line of travel of that feeder-hand shoe which is in engagement with the receiving tray, means for imparting vibratory movement to the rack-bar whereby said shoe is moved intermittently throughout the length of the receiving tray while the opposite shoe is idly moving to a starting point, and means for rotating the runway co-incident to a completion of a feed stroke of its feeder-hands whereby the previous idle feeder-hand is brought into working position.

20. A slab-cutting and separating machine comprising a table, a series of alined fixed cutters extending above the table, a slab-engaging follower strip arranged to one side of the cutters, actuating means for the follower strip whereby a slab of material is fed through the series of cutters and divided into cubes, a rocking separator disposed adjacent to one line of cutters and upon that side opposite the follower strip, actuating means therefor, a cube-feeder arranged transversely of the cutters in line with the separator, intermittent actuating means therefor, means for shifting the cube-feeder incidental to the completion of a working movement thereof, a spotter-foot disposed adjacent to one edge of the follower strip, actuating means therefor, a presser-foot arranged to engage the cubes forwardly of the separator, actuating means therefor, a

drive-shaft, cams carried by the shaft for imparting movement to the presser-foot, separator and intermittent feed mechanism of the cube-feeder, a pair of cams loosely mounted upon the driven shaft for imparting movement to the follower strip, spotter-foot and cube feeder shifting means, and a back gear train connecting the driven shaft and said pair of cams whereby the latter are 10 rotated at a reduced speed relative to the speed of said shaft.

21. A slab-cutting and separating machine comprising a line of spaced cutting members, means for feeding strips of material thereto upon one side of the cutting members, a receiving tray upon the opposite side thereof, a pair of oppositely disposed feeder-hands in belt connection, the same being at a distance apart equal to the distance between the first and last cutting member, means for alternately swinging the feeder-hands into a working position with relation to the receiving tray, and means for causing travel of that feeder-hand which is 20 in working position intermittently at distances equal to the distance between said cutting members.

22. A cutting machine of the character described comprising a line of cutting members, an intermittently rotatable belt of greater length than the distance between the first and last cutting member arranged to travel parallel with said cutting members, a feed member extending from each stretch of 35 the belt, and an intermittent actuating feed mechanism for one of the belt stretches.

23. In a machine of the character set forth, the combination of a table, a slab-feeding follower, a series of cutters adapted 40 to sever a slab into prints, a print-series runway disposed adjacent one edge of said table and a little below the table level, and means for moving the series of prints along said runway.

24. In a machine of the character set forth, the combination of a table equipped at one edge portion with a guide, a suitably actuated slab-positioning member arranged 50 opposite said guide, a slab-feeding follower having one end adjacent said guide, a series of slab-cutting devices adapted to sever the slab into prints, a print-series runway, and means for intermittently moving a series of prints along said runway.

25. In a machine of the character set forth, the combination of a table equipped at one edge portion with a guide, a suitably actuated slab-positioning member arranged 60 opposite said guide, a slab-feeding follower having one end adjacent said guide, a series of slab-cutting devices adapted to sever the slab into prints, a print-series runway, means for intermittently moving a series of prints along said runway, and a print-sepa-

rating device adapted to receive the prints 65 *seriatim* and advance them singly.

26. In a machine of the character set forth, the combination of a table, a print-series runway adjacent one edge thereof, a slab-follower movable toward and away 70 from said runway, a series of cutters between said follower and said runway, a print-engaging member movable along said runway, means for intermittently advancing said print-engaging member, and means for 75 periodically actuating said slab-feeding follower.

27. In a machine of the character set forth, the combination of a table, a print-series runway adjacent one edge thereof, a 80 slab-feeding follower, a series of cutters interposed between the follower and runway, a revolute print-series feeding device adjacent to the runway, means for intermittently actuating the print-feeding device, and periodically-operating means for simultaneously actuating said slab-feeding follower and turning said print-series feeding device. 85

28. In a machine of the character set forth, the combination of a table, a print-series runway at one edge thereof, a slab-feeding follower, a series of cutters disposed between said follower and said runway, a slab-positioning member movable at right-angles to the path of movement of said follower, a revolute print-series feeding-device, means for intermittently actuating the same, and periodically-operating means serving to actuate said slab-positioning member and said slab-feeding follower and 100 turn said print-series feeding-device.

29. In a machine of the character set forth, the combination of a table, a print-series runway at one edge thereof, a slab-feeding follower, a series of cutters disposed 105 between said follower and said runway, a revolute print-series feeding-device, a shaft equipped with a cam serving to actuate said print-series feeding-device, a tubular shaft mounted on said first-named 110 shaft, means for rotating said shafts at different rates of speed, and cam means on said tubular shaft serving to periodically actuate said slab-feeding follower and turn said print-series feeding-device. 115

30. In a machine of the character set forth, the combination of a table adapted to receive a slab of material, a series of alined, fixed cutters extending above the table, means for feeding a slab of material through 120 the cutters whereby it is divided into prints, means for advancing the row of prints intermittently parallel with said line of cutters, and a print-separator adapted to receive the advance print of the series and 125 feed it forward individually.

31. In a machine of the character set forth, the combination of a table, a series of

aligned cutters extending above the table, a slab-engaging follower-strip slidably mounted upon said table at one side of said cutters and adapted to feed a slab through the cutters and thus divide the same into cubes, a feeder-hand arranged to travel parallel with the cutters, and a separator in alignment with the path of travel of said feeder-hand and adapted to receive the cubes as they are successively advanced thereto.

32. In a machine of the character set forth, the combination of a table, a series of aligned cutters extending above the same, a slab-feeding follower above said table, an intermittently-movable feeder-hand arranged to travel parallel with the cutters, a separator in alignment with the path of movement of said feeder-hand and adapted to receive the cubes as they are successively advanced thereto, an actuating-cam and means actuated thereby for actuating said separator, an actuating-cam and means actuated thereby for moving said feeder-hand intermittently, means for driving said cams at the same rate of speed, a cam serving to actuate said follower-strip, and means for driving said last-named cam at a slower speed than said first-mentioned cams.

33. In a machine of the character set forth, the combination of an aligned series of cutters, a receiving-tray disposed at one side of said line of cutters and parallel thereto, a slab-feeding follower disposed at the opposite side of said aligned cutters, a revolute member adjacent the receiving-tray and equipped with an endless belt, feeder-hands carried by said belt, means for imparting intermittent movement to the feeder-hands, and means for turning said revolute member after a feeder-hand has traversed the length of said tray.

34. In a machine of the character set forth, the combination of a series of cutters, slab-feeding means adapted to feed a slab through said cutter, whereby the slab is severed into prints, a print-series runway on the opposite side of said cutters, an independently-movable separator at one end of the print-series runway, a revolute member parallel with the print-series runway, feeder-hands mounted on said revolute member and adapted to travel in opposite directions along the same, means for releas-

ing and locking said revolute member, cam-controlled actuating means for said releasing and locking means, and actuating means for the feeder-hands.

35. In a machine of the character set forth, the combination of a series of cutters, slab-feeding means adapted to feed a slab through said cutters and cause the same to be divided into cubes, a receiving-tray arranged parallel with the line of cutters on the side opposite the slab-feeding means, a revolute member parallel with said tray, means for turning said revolute member, cam-controlled lock-and-release means in connection with said revolute member, feeder-hands mounted on said revolute member and extending in opposite directions, a belt carried by said runway, means for adjustably securing the feeder-hands to said belt, and intermittent feed-mechanism for the belt-connected feeder-hands.

36. In a machine of the character set forth, the combination of slab-feeding means, a series of spaced cutters, a receiving-tray, a pair of belt-connected feeder-hands spaced apart a distance corresponding with the first and last cutting members, means for alternately swinging the feeder-hands into working position with relation to the receiving-tray, and means for imparting working movement to one feeder-hand and idle return movement to the other feeder-hand.

37. In a machine of the character set forth, the combination of a series of cutting devices, a periodically-positioned belt one portion of which is adapted to travel adjacent said cutting members, a feed member extending from each stretch of said belt, and intermittently-operating means serving to actuate said belt and the cutter-members carried thereby.

In testimony that we claim the foregoing we have hereunto set our hands at Milwaukee in the county of Milwaukee and State of Wisconsin in the presence of two witnesses.

FREDERICK H. MERRELL.
